UNITED STATES PATENT OFFICE

ALBERT L. LAMBERT, OF NARBERTH, PENNSYLVANIA, ASSIGNOR TO HEINTZ MANUFACTURING COMPANY, A CORPORATION OF PENNSYLVANIA

FIN RADIATOR

Application filed October 15, 1931. Serial No. 568,943.

The present invention relates to fin radiators and like heat exchange apparatus, and an object of the invention is to provide an improved device of this character and a novel 5 and particularly efficient form of fin therefor.

Another object of the invention is to provide a construction of radiator fin in which a better flow of heat through the fin is secured than heretofore, and thus insure a 10 more effective distribution of the heat therein, and to eliminate the cold spots which frequently exist in fins as they have heretofore been made, and thus secure more efficient radiation.

15 A further object is to provide increased air space between portions of adjacent fins where the temperatures are lowest and where the draft head due to air temperature differences is correspondingly low, and thus provide a corresponding decrease in friction 20 between such portions and the current of air passing thereover.

A still further object is to reduce the weight of the material utilized in radiator 25 fins and therefore economize in the cost of the material, to reinforce the fins against accidental bending or other damage at the points where such damage as would tend to obstruct the air passages is most likely to 30 occur, and to strengthen the fins where they are attached to the radiator tubes.

The various features of novelty which characterize my invention are pointed out with particularity in the claims annexed to 35 and forming a part of this specification. For a better understanding of the invention, however, and the advantages possessed by it, reference should be had to the accompanying drawing and descriptive matter in which I 40 have illustrated and described certain embodiments of my invention.

In the drawing:

Fig. 1 is a transverse sectional view of a 45 double section, four-tube radiator having my invention embodied therein;

Fig. 2 is a vertical longitudinal sectional view taken on the line 2—2 of Fig. 1;

Fig. 3 is a horizontal longitudinal sectional view taken on the line 3—3 of Fig. 1;

50 Fig. 4 is a perspective view of a single sec-

tion, two-tube fin embodying my invention;

Fig. 5 is a perspective view of a double section, two-tube fin embodying my invention; and

Fig. 6 is a perspective view of a single section, one-tube fin embodying my invention. 55

As shown in Figs. 1, 2 and 3, my radiator fin comprises a plate member 1 having a central longitudinal section 2 of substantially uniform thickness throughout its extent. 60 Extending from each lateral edge 3 of the central longitudinal section 2 and integrally formed with respect to the section 2 is a marginal section 4 which decreases in thickness gradually from the central longitudinal section to the outer edge 5 of the marginal section. In the embodiment of my invention shown in Figs. 1, 2 and 3, which may be described as a double section, four-tube type of fin, two of the fin sections just referred to are 65 united together along their lateral edges as shown at 6.

In order that these fins may be assembled 70 in connection with suitable tubular conductors for a heating medium, I provide openings 7 through the central longitudinal thickened sections 2 of the fins and these openings are preferably surrounded by a flange 8 on one side of the fin. The openings 7 are 75 preferably made by a punching process 80 whereby the flanges 8 are simultaneously produced. These openings and the surrounding flanges provide means whereby the fins may be assembled upon the tubular conductors 9 for a heating medium, and the flanges 85 serve the purpose of strengthening the fins at their points of attachment to the tubular conductors, and prevent the fins from readily being bent out of their normal position with respect to the tubes. 90

In using the form of my invention illustrated in Figs. 1, 2 and 3 of the drawing, it will be understood that the radiator in which my improved fins are incorporated will be so positioned that the central longitudinal 95 sections 2 of the fins extend in the direction of the convection currents of air. Ordinarily the fins will be so placed that the central longitudinal sections 2 are arranged vertically. It will be obvious, however, that these 100

sections may be arranged to extend in a horizontal direction in case the radiator is employed with a forced draft produced by a fan or other similar device. The purpose of the relatively thick central longitudinal sections which I employ in the fins is to provide, in effect, an elongated or oval tube. From principles which are well known, it will be understood that heat will be conducted freely from the tubes 9 through the central longitudinal sections 2 of the fins, and that it will be transferred to a lesser extent directly from the tubes 9 transversely of the fins to the marginal sections 4. As a result of this, the central longitudinal sections 2 are heated more or less evenly throughout their length, whereupon transfer of the heat takes place laterally from the longitudinal sections 2 to the marginal sections 4 so that these marginal sections become heated much more uniformly throughout their length than they would if the relatively thick longitudinal section were not present. This results in the elimination of cold spots from those portions of the fins with which the convection currents come into contact, thus producing more efficient radiation.

In making the fins in which my invention is embodied, I prefer to utilize strips of material, either copper or aluminum, or suitable alloys thereof, of sufficient width to form the double fin sections as shown in Figs. 1 and 5. These strips are then rolled in such a manner as to provide the central longitudinal sections 2, substantially uniform in thickness, and the beveled marginal sections 4. The stock thus formed comprises a double section which may readily be severed transversely to provide the double section, four-tube fin illustrated in Figs. 1, 2 and 3. In case a double section, two-tube fin is desired, this stock may be severed transversely to provide a fin of the type shown in Fig. 5. In case a single section, two-tube fin is desired, the stock may be severed both longitudinally and transversely to form a fin such as shown in Fig. 4, and a further severance of the fin shown in Fig. 4 will provide a single section, one-tube fin of the type illustrated in Fig. 6.

The manner in which my improved construction of fin functions when a plurality of such fins are assembled on a radiator tube will be clear from the above description. The number of tubes employed, likewise the number of fins upon the tubes, will be dependent upon the requirements of the particular case. In some cases it may be desirable to employ fins of the type illustrated in Fig. 1 of the drawing; under other conditions it may be desirable to utilize the type shown in Fig. 4; under still other conditions the type of fin shown in Fig. 5 may be advantageously employed; or the type shown in Fig. 6 may be conveniently used under proper

circumstances. It is to be understood that the various types illustrated are merely representative of the forms which my invention may take, and other arrangements may readily be resorted to as conditions require. In any case, irrespective of the number of tubes employed and irrespective of the extent to which fins of the type shown in Fig. 6 are multiplied to form fins of greater area, as illustrated in Figs. 1, 4 and 5, heat from the radiator tube will be conducted freely throughout the length of the thick longitudinal sections, which, when the radiator is in use, are arranged to extend in the direction of the convection currents. The relatively thick longitudinal sections of the assembled fins thus have the effect of a radiator tube having a cross section corresponding to the area of one face of each of the central longitudinal sections of the fins, and they become heated substantially uniformly throughout their length. From the central longitudinal section heat is conducted transversely into and across the marginal sections 4 of each fin so that these sections are likewise heated more or less uniformly throughout their length.

As heretofore explained, my improved fins are so arranged when in use that the central longitudinal sections 2 extend in the direction of the convection currents, consequently the marginal sections 4 of the fins extend in the same direction, and inasmuch as each marginal section decreases in thickness from the central section outwardly toward the lateral edge 5 of the marginal section, the cross sectional area of the air space between adjoining fins is greater than it would be if the marginal sections did not decrease in thickness toward their edges in this manner. This increased air space results in a corresponding decrease in friction between the moving current of air and the marginal sections of the fins, and as the draft head decreases as the distance from the central longitudinal section increases transversely of the marginal section, due to the temperature difference, it will be seen that the decrease in thickness of the marginal sections 4 toward their lateral edges 5 is an important feature of my invention.

In addition to the advantage heretofore described for the construction of my improved fin whereby the central thickened longitudinal section 2 functions as a tube of elongated cross-section to transfer heat longitudinally throughout the fin, the thickened portions also provide a more substantial support for a radiator in which a number of the fins are assembled. Ordinarily such a radiator will rest on the floor or other suitable support before installation, and the thickened portions of the fins prevent the fins from being bent and damaged, as would be likely to occur if they were not present. This construction also provides a means for prevent-

ing the upper ends of the fins from being damaged, either before or after the installation of the radiator, when tools or other articles are accidentally dropped upon it. It

5 will be understood, of course, that radiator fins of this general character are ordinarily made from comparatively thin metal stock, so that the danger of damage in this manner is not negligible.

10 The construction which I have provided wherein the openings 7 for the tubes 9 are located in the thickened central sections 2 is also an important feature of my improvement. By making the fins in this manner, the flanges 8 surrounding the openings 7 are necessarily turned outwardly from the thick central section, and thus serve to prevent the fins from being bent or deformed to any considerable extent when the fins are in position 15 on the radiator tube. In this connection it will be observed that the width of the central section 2 of my fin is slightly greater than the diameter of the tube employed therewith so that the additional strength of the central section is availed of in providing the flange 20 by which the fin is supported upon the tube and by means of which it may be secured to the tube in any suitable manner.

25 While I have shown and described a particular form which my invention may take and certain embodiments of it, it is to be understood that various changes in construction and arrangement may be made without departing from the spirit of my invention 30 as set out in the appended claims. It will be understood, for example, that the shape of the marginal sections 4 of my fin need not be such that there is a gradual decrease in thickness from the central longitudinal section 2 outwardly toward the free lateral edge 5 of the marginal section. In some cases it may be desirable to provide an abrupt shoulder where the adjoining sections meet along the line 3, and in other cases a gradual slope may 35 be provided at this point. Irrespective of the particular manner in which the juncture of the two sections 2 and 4 is made, it will be obvious that the marginal sections 4 may taper from the central longitudinal section to 40 its outer edge, or it may be of uniform thickness throughout its width, the essential requirement in this respect being that the conductivity of the central longitudinal section in the direction of the convection currents be 45 such as to substantially exceed the conductivity of the marginal sections in a direction transversely thereof. This can, of course, be accomplished by making the central longitudinal section of a thickness substantially 50 greater than the marginal sections, or the same result may be obtained by the use of a material for the central longitudinal section having a higher thermal conductivity than the material utilized for the marginal 55 sections, in order that uniform distribution 60

of heat throughout the length of the central longitudinal section of the fin may be obtained.

What I desire to secure by United States Letters Patent is:

1. In a radiator construction, the combination of a plurality of spaced, parallel fins each comprising a plate member having a central section of substantially uniform thickness adapted to extend in the direction of the convection currents, and a marginal section secured to each lateral edge of the central section and decreasing in thickness from the central section outwardly to the lateral edge of the marginal section, the central sections of the plate members extending throughout the length of the fins; and being provided with alined openings punched therein to provide a surrounding flange on one side of the plate members, and a tubular conductor for a heating medium extending through said openings.

2. In a radiator construction, the combination of a plurality of spaced, parallel fins each having a plane face and comprising a plate member having a central section of substantially uniform thickness adapted to extend in the direction of the convection currents, and a marginal section secured to each lateral edge of the central section and decreasing in thickness from the central section outwardly to the lateral edge of the marginal section, the central sections of the plate members extending throughout the length of the fins and being provided with alined openings and a flange projecting from the plane face of the central section of each plate member around the opening therein, and a radiator tube extending through said alined openings.

In testimony whereof, I have signed my name to this specification.

ALBERT L. LAMBERT.
